ABSTRACT: A mincing machine having at least one perforated disc and relatively rotatable blade means operably associated with said disc. The blade means are carried by a blade-holder which is axially displaceable relative to the perforated disc. Biasing means for biasing the blade-holder towards the disc so that the blades are resiliently pressed against the disc surface.

MINCING MACHINE

BACKGROUND OF THE INVENTION

The invention relates to a mincing machine, preferably for meat. The invention is particularly concerned with a mincing machine having at least one perforated disc over which knife-blades rotate; the blades are movably held in a multiarmed knife-head and resiliently pressed against the perforated disc, those surfaces of the arms of the knife-head which are to the front in the circumferential direction being at an acute angle to the surface of the perforated disc.

Such a mincing machine is shown in German Pat. specification No. 1167214. The fact of the knife-blades of this mincing machine, being held in movable fashion, and being resiliently pressed against the perforated disc, compensates for departures from the parallel relative attitude of the knife-head and perforated disc, unless those departures have been intentionally introduced as a result of the perforated disc being obliquely set or have occurred unintentionally in consequence of tolerances in production and assembly, and guarantees that the knife-blades exert substantially constant pressure on the perforated disc under all conditions and circumstances of operation. This reduces frictional wear, the more so since the spring biased knife-blades can to a certain extent avoid particularly hard bone and gristle components in the material being minced, and such components need not be completely minced immediately upon first being picked up.

It has however now appeared that the knife arrangement of German Pat. specification No. 1167214 is disadvantageous to the extent that the knife-blades which are individually and movably guided and sprung in slits in the knife-head easily become jammed if any of the material being minced sticks in the slits and on the spring biasing elements. The knife-blades are then no longer capable of developing their action described above.

A mincing machine according to the invention has at least one perforated disc and a multiarmed knife-head mounted for rotation adjacent the disc and comprising a precutter which is substantially axially fixed relative to the disc and which has arm elements constituting the leading parts of the knife-head arms and having leading faces at an acute angle to the surface of the disc, a blade-holder which is axially displaceable relative to the precutter and the disc and which has arm elements constituting the trailing parts of the knife-head arms, knife-blades carried by the blade-holder arm elements between the precutter and blade-holder arm elements, and biasing means for biasing the blade-holder toward the disc so that the blades are pressed against the blade surface.

Since the biasing means may readily be arranged so that it is not exposed to the action of the material being minced, there is no danger of the springing of the knife-blades being obstructed. In this connection, the fact that the knife-head is separated into the precutter and blade holder preserves unaffected the axial relative attitude of those front surfaces of the arms of the knife-head which are disposed obliquely with respect to the perforated disc, and which set up a pumping action which conveys the material being minced through the machine, while the blade-holder together with the knife-blades can move axially in relation to the precutter.

Automatic adaption of the knife-blades to the position of the perforated disc is further encouraged if, as is preferred, the blade-holder is arranged to rock slightly on the driving shaft.

The arrangement according to the invention has a particularly advantageous effect when applied to mincing machines having a plurality of knife-heads and perforated discs. While it has hitherto been necessary to take care that mutual clearances between the knife-heads were exactly equal to the clearances between the associated perforated discs, the arrangement according to the invention may not involve the necessity for any rigid common alignment of the individual mincing stages. It is therefore readily possible for unskilled hands to put together the individual parts after the replacement of worn parts or after cleaning.

If there is a plurality of knife-heads sequentially arranged on one driving shaft, a further development of the invention involves the precutters being clamped fast against one another, while the biasing means exerting pressure on the blade-holders 5 are in each case supported on the neighboring precutter or shaft-termination. It has transpired that in the case of such an arrangement there is a continuous ventilation path along the driving shaft where the air aspirated with the material being minced collects because of its low specific weight.

10 Above all in the case of such a multistage arrangement, effective ventilation of the material being minced can be encouraged by placing the space in the region of the hub between the precutter and the blade-holder in communication with suction.

15 The biasing means which exert pressure on the blade-holder may be a spiral spring concentric with the driving shaft. However, it may also be a gas-filled annular space concentrically surrounding the driving shaft and subjected to externally adjustable pressure, of for example a liquid under pressure. The latter form of biasing means may with advantage have control means so arranged that there is no pressure in the annular space when the machine is idling, and the material entering the machine actuates a switching member which enables a predetermined working pressure to take effect in the annular space.

It is known that the knife-blades of the high-speed knife-head ought not to be pressed against the perforated disc without the cooling action of cooked meat running through.

20 Mechanical constructions enabling the knife-head to be manually withdrawn from the perforated disc in the absence of any material for mincing entering the machine have therefore already been proposed. The method according to the invention of controlling the pressure in an annular space filled with gas and if desired also with liquid, and acting on the blade-holder, solves this problem in a better way, the more so since the control means may be regulated in direct dependence on the entry of material for mincing into the machine, the material actuating a pressure-switch or mechanical switch.

25 The invention will be more readily understood by way of example from the following description of a meat-mincing machine in accordance therewith, reference being made to the accompanying driving in which:

30 FIG. 1 is a side view of a three-stage meat mincing machine, the upper half being shown in axial section,

35 FIG. 1a is a section along the line A-B in FIG. 1,

FIG. 2 is a plan view of the knife-head and perforated disc or a mincing stage,

FIG. 3 is a perspective exploded view of the parts shown in

40 FIG. 2, and

FIG. 4 is a sectional view corresponding to FIG. 1 but on an enlarged scale through the first mincing stage, but with a modified biasing arrangement, a preferred form of control means for said modified arrangement being illustrated schematically.

45 As shown in the drawings, the mincing machine has a cylindrical housing 1 of the mincing stages within which are mounted three perforated discs 2 spaced away from one another, and having perforations of decreasing diameter and increasing number in the direction in which the material being minced is conveyed (arrow 3). The discs 2 are spaced by cutting rings 4 which are in the form of cylindrical sleeves with inwardly projecting teeth 5, and which abut the discs 2 adjacent their peripheries, the assembly of discs and cutter rings

50 being clamped within the housing 1 between a rib formed at the forward end of the housing and a nut 6. Each of the discs 2 has a knife-head designated as a whole by 8, and having a knife-blade 9 bearing against the associated disc 2. The three knife-heads 8 are arranged on a shaft 7 running coaxially in the housing 1, and having the cross-sectional shape shown in FIG. 1a; the bearings for the shaft are not illustrated. Each knife-head 8 consists essentially of a precutter 10 and a blade-holder 11, of which the hollow hubs 12 and 13 respectively fit concentrically one into the other (FIGS. 2 and 3). As best

55 shown in FIG. 2, each knife-head has three arms of each of

which the leading element 15 is a component of the precaster and the trailing element 16 is a component of the blade-holder 11. In FIG. 1, the precaster is illustrated by only the hub 10 with its annular shoulder 14 at one end and the outermost tip of the front part 15 of one arm of the knife-head projecting beyond the associated rear part 16.

The hub 12 of each precaster 10 has cutaways 17 in which correspondingly shaped portions 18 of the arm elements 16 of the knife-head arms fit (FIG. 3). As shown in FIGS. 1 and 1a, the shoulder 14 of each hub 12 has a bore shaped similarly to the polygonal cross section of the shaft 7, so that the precasters are rotated with the shaft; on the other hand, the bore 20a in the corresponding shoulder 20 of the hub 13 of each blade-holder 11 is larger than the maximum shaft diameter and the blade-holders are therefore not linked in torque-transmitting manner with the shaft 7. On the outside of the hub 13 of each blade-holder 11 there are projecting radial segments 13a which are shown in FIG. 1a and which engage the interior of hub 12 and therefore keep the blade-holder concentric while leaving a certain amount of play for compensating for production tolerances. When the shaft 7 rotates, the blade-holder 11 is moved with the precaster 10 by virtue of the engagement of the edges of the cutaways 17 with the portions 18 of the rear arms 16 of the knife-head; as a result there is a positive driving link between each precaster 10 and its blade-holder 11. The driving link between the precaster 10 and the shaft 7 may also be set up, as the modification illustrated in FIGS. 2 and 3 shows, by a spring fitting on the shaft 7 and a groove 19 surrounding the latter in the shoulder 14 of the precaster hub 12.

As FIG. 1 particularly reveals, the cutaways 17 in the hollow hub 12 of the precaster 10 are deeper in the axial direction than the height of the portions 18 of the trailing arm elements 16 of the knife-head arms. This gives the blade-holder 11 a certain amount of axial mobility in the precaster 10. This mobility is unhindered by the clamping of the three hubs 12 of the precasters 10 against one another between a shoulder 21 on a rotary pump wheel 22 and a ring nut 23; this wheel 22 sets up suction downstream of the mincing stages and ejects from the machine the minced material emerging through the perforated disc 2 of the last stage.

Thus while the precasters 10 are held against axial movement relative to the shaft 7, the blade-holders 11 are capable of axial displacement since each is disposed with some play in the hubs 12 of the associated precaster and therefore on the shaft 7; each blade-holder 11 can also rock to some extent. However, a spiral spring 24 inserted between the shoulder 20 of the hub 13 of each blade-holder 11 and the shoulder 14 of the hub 12 of the neighboring precaster 10 or the ring 23, and concentrically surrounding the shaft 7, presses each blade-holder 11 against the associated perforated disc 2. As a result, the knife-blades 9 of each knife-head bear against the associated perforated disc 2.

The knife-blades 9 are mounted by means of holes 25 on pins 26 projecting in the circumferential direction from those surfaces of the rear arm elements 16 of the blade-holder 11 that are to the front in the direction of rotation 27. The slit formed between the arm elements 16 of the blade-holder 11 and the arm elements 15 of the precaster 10 is sufficiently narrow to prevent the knife-blades 9 from dropping off the pins 26, but sufficiently wide to ensure that the knife-blades 9 can pivot unhindered on their pins. Grooves 28 in those surfaces of the arm elements 15 are to the rear in the direction of rotation, and that facing the knife-blades 9, ensure the dispersal of any material being minced that may penetrate between the knife-blades 9 and those surfaces of the elements 15.

Accordingly, through the resilient biasing action of spring 24, the pivotal mounting of blades 9 and the ability of blade-holder assembly 11 to rock slightly, the blades 9 may adjust to avoid particularly hard bone and gristle components in the material being minced. This ability of the blades 9 to adapt, materially reduces the frictional wear thereon.

The leading surfaces 29 of the leading arm elements 15 of the precaster 10 extend in known manner obliquely to the per-

forated disc 2. They are advantageously followed by a surface 30 extending substantially parallel to the perforated disc 2 and retaining the material to be minced that has collected by the oblique surfaces 29 until it is minced by the knife-blades 9 in conjunction with the perforations in the associated disc 2, so that the material is prevented from "dancing" in front of the knife-blades 9. The space 31 between the hubs of the precaster 10 and the associated blade-holder 11 of the last knife-head 8 (at the left in FIG. 1) may be placed in communication with suction via a bore 32 passing through the hub-plate of the pump rotor 22, so that the air which collects in the hub region of that knife-head 8 is aspirated off. FIG. 1 shows similar bores for the other two knife-heads 8 passing through the hubs 14 so that the spaces 31 of all the mincing stages are in communication parallel to the shaft 7.

FIG. 4 shows a cutaway portion of a modified design of the means of resiliently pressing the blade-holder 11 against the perforated disc 2. Instead of the spiral spring 24 of FIGS. 1 and 2, a pistonlike, pressure operated arrangement is employed. As can be seen in FIG. 4, an annular air-filled ring 33 is disposed against the shoulder 20 of the hollow hub 13 of the blade-holder 11. The ring 33 is accommodated in an annular space 34 defined internally by the shaft 7 and externally by the hub 13, on one face by the shoulder 20 and on the other face by a sleeve 35 inserted into the hollow hub 13. Said sleeve 35 abuts against the ring 33 to limit axial movement thereof in one direction. The sleeve 35 carries annular sealing elements 40 and 42, which engage the inner bore of the hub 13 and the external surface of shaft 7, respectively. In addition, shoulder 20 may carry an annular packing member 44 which sealingly engages shaft 7. Accordingly, it may be seen that the annular space 34 is substantially fluidtight, except for its communication with a source of fluid under pressure, as will be detailed hereinafter. Also, ring 33 includes annular sealing lips 36 to insure that pressurized fluid does not leak past said ring.

Annular space 34 communicates with a source of fluid under pressure via an axial shaft bore 37 and a transverse bore 38. Thus, upon the introduction of fluid under pressure into the annular space 34, the fluid will exert an axial force on shoulder 20 via the ring 33, which force is effective to move the blade-holder 11 and its associated blades 9 toward and against the perforated disc 2. If the pressurized fluid is withdrawn from the chamber 34 or the pressure head in said chamber is reduced in some other manner, the blades 9 will not be forced into engagement with the disc 2 and will move freely therewith. Thus, since the meat being processed provides a cooling action for blades 9, once processing thereof is completed the pressure in annular space 34 is reduced to avoid undue wear on blades 9.

As was the case with the previously discussed embodiment, the blades 9 of the embodiment of FIG. 4 may also adapt, so that they can to a certain extent avoid hard bone and/or gristle. This is accommodated for by providing that the biasing force exerted by the pressurized fluid is such as to permit slight retraction of the blade holder 11 when bone or gristle is encountered.

The particular fluid employed to move the blade-holder 11 is a matter of choice, water, air pressure or the like being anticipated.

A preferred control system for the pressure operated arrangement just described is illustrated schematically in FIG. 4. In this regard, a switch 46 is positioned within the mouth or entry portion of a hopper 48 that is associated with the mincing machine of the present invention. The switch 46 is normally opened and positioned such that it will be actuated by material being introduced into hopper 48, which engagement biases the switch to the closed condition. Once switch 46 is closed, solenoid 50 is placed in circuit with a source of power 52 to energize the solenoid coil, and move the solenoid actuator rod 54 downwardly. The actuator rod 54 is operably joined to a piston member 56 of a fluid cylinder arrangement 58 to effect movement thereof in the direction indicated. The fluid cylinder 58 has an outlet port 60 which communicates with a

fluid line 62 which in turn is associated with the shaft bore 37. Accordingly, upon energization of solenoid 50, piston 56 will move downwardly forcing fluid out of cylinder 58, thus increasing the fluid pressure in line 62 and correspondingly, in the annular space 34 via bores 37 and 38.

While the material to be processed engages switch 46, the circuit to solenoid 50 will be closed and the blades 9 biased into engagement with discs 2. Since it is desirable for the biasing of blades 9 to continue after the last portion of material passes switch 46, so that the mincing process may be completed, switch 46 is preferably of a type which will remain closed for a short period of time after engagement by material in hopper 48 ceases. A wide variety of switches of this type are available, as are other means for effecting the same end result, and further explanation is not deemed necessary.

In the example or embodiment illustrated, the knife-heads 8 have three arms, but it is to be understood that each knife-head may have two or more than three arms as required. Also, it is envisioned that various other changes, modifications and substitutions may become readily apparent to one skilled in the art from the foregoing description. It is intended that said modifications or changes shall be within the scope of the present invention insofar as they are encompassed by the claims appended hereto.

The invention I claim is as follows:

1. A mincing machine including; at least one perforated disc; a multiarmed knife-head mounted adjacent said disc for relative rotation therebetween, and said knife-head comprising, a blade-holder which is axially displaceable relative to said disc, a plurality of knife-blades carried by said blade-holder, and a precutter which is substantially axially fixed relative to the disc and which has arm elements constituting the leading parts of the knife-head arms and having leading faces at an acute angle to the surface of said disc, said blade-holder being axially displaceable relative to said precutter and having arm elements constituting the trailing parts of the knife-head arms, said precutter and blade-holder arm elements carrying the knife-blades therebetween; and biasing means for biasing the blade-holder and its associated blades axially toward said disc such that said blades are resiliently pressed against the disc surface.

2. A mincing machine as defined in claim 1 wherein the blade-holder is mounted for slight rocking movement relative to said disc.

3. A mincing machine as defined in claim 1 wherein the knife-blades are pivotably carried by the blade-holder.

4. A mincing machine as defined in claim 1, wherein both the precutter and the blade-holder have hollow hubs, the precutter hub coaxially surrounding the blade-holder hub which has projecting elements thereon engaging in recesses formed in said precutter hub, whereby said precutter and blade-holder will rotate together with relative axial movement therebetween being permitted.

5. A mincing machine as defined in claim 4, wherein said machine includes a driving shaft, said shaft having the precutter nonrotatably affixed thereto, whereby said precutter will drive the blade-holder by means of the interengaged projecting elements and recesses on said precutter and said blade-holder.

6. A mincing machine as defined in claim 4, wherein the space between said coaxial hubs on the precutter and blade-holder, respectively, communicates with suction.

7. A mincing machine according to claim 1, wherein the blade-holder includes a hub and a radially inwardly extending flange against which the biasing means acts to resiliently press the blades against the disc surface.

8. A mincing machine as defined in claim 7, wherein said biasing means is a spiral spring engaging said radially inwardly extending shoulder on the blade-holder hub.

9. A mincing machine according to claim 1, wherein said biasing means includes a fluid-operated arrangement.

10. A mincing machine as defined in claim 9, wherein said fluid-operated arrangement includes: a radially inwardly extending annular flange on said blade-holder, structure cooperating with said flange to define an annular enclosed

space; sealing means for rendering said space substantially fluidtight; and fluid conduit means in communication with said space and adapted to be connected to a source of fluid under pressure whereby upon the introduction of fluid under pressure into said space said axial movement of the blade-holder relative to the disc may be effected.

11. A mincing machine as defined in claim 10, wherein said fluid-operated arrangement includes an annular, air-filled ring disposed in engagement with said inwardly extending flange on the blade-holder, and upon which fluid under pressure will act for transmission of axial force to said flange.

12. A mincing machine as defined in claim 9, further including control means for activating said fluid-operated arrangement upon material being minced entering said machine.

13. A mincing machine including: at least one perforated disc; a multiarmed knife-head mounted adjacent said disc for relative rotation therebetween, and said knife-head comprising, a blade-holder which is axially displaceable relative to said disc and includes a plurality of knife-blades; remotely controlled biasing means for biasing the blade-holder axially into engagement with said disc, said remotely controlled biasing means including sensing means operated by entry of material to be minced into said machine to actuate said biasing means.

14. A mincing machine including: at least one perforated disc; a multiarmed knife-head mounted adjacent said disc for relative rotation therebetween, and said knife-head including a blade-holder which is axially displaceable relative to said disc, a plurality of knife-blades carried by said blade-holder, and a precutter which is substantially axially fixed relative to the disc and which has arm elements constituting the leading parts of the knife-head arms and having leading faces at an acute angle to the surface of said disc, said blade-holder being axially displaceable relative to said precutter and having arm elements constituting the trailing parts of the knife-head arms, said precutter and blade-holder arm elements carrying the knife-blades therebetween; and means defining an annular space between said precutter and said blade-holder and adapted upon the introduction of fluid under pressure into said space to bias said blade-holder axially to engage said disc; and control means for selectively applying liquid under pressure to said annular space.

15. A mincing machine as defined in claim 14, wherein said control means includes; sensing means operated by entry of material to be minced into said mincing machine; means for applying liquid under pressure to said annular space; and means operated by said sensing means for actuating said applying means.

16. A mincing machine including: at least one perforated disc; a multiarmed knife-head mounted adjacent said disc for relative rotation therebetween, and said knife-head comprising, a blade-holder which is axially displaceable relative to said disc, and a plurality of knife-blades carried by said blade-holder; and biasing means for biasing the blade-holder and its associated blades axially toward said disc such that said blades are resiliently pressed against the disc surface, said biasing means including a fluid-operated arrangement, said arrangement including a radially inwardly extending annular flange on said blade-holder, structure cooperating with said flange to define an annular enclosed space, sealing means for rendering said space substantially fluidtight, and fluid conduit means in communication with said space and adapted to be connected to a source of fluid under pressure whereby upon the introduction of fluid under pressure into said space said axial movement of the blade-holder relative to the disc may be effected.

17. A mincing machine as defined in claim 16, wherein said fluid-operated arrangement includes an annular, air-filled ring disposed in engagement with said inwardly extending flange on the blade-holder, and upon which fluid under pressure will act for transmission of axial force to said flange.

18. A mincing machine as defined in claim 16, further including control means for activating said fluid-operated arrangement upon material being minced entering said machine.
